CLAIM

The ornamental design for an end cap for an open end of a filter housing, as shown and described.

DESCRIPTION

FIG. 1 is a front isometric view of an end cap for an open end of a filter housing of the present invention.

FIG. 2 is a top view of the end cap for an open end of a filter housing shown in FIG. 1.

FIG. 3 is a bottom view of the end cap for an open end of a filter housing shown in FIG. 1.

FIG. 4 is a side view of the end cap for an open end of a filter housing shown in FIG. 1, wherein the other side is identical.

FIG. 5 is an enlarged view of the detail shown in FIG. 4.

FIG. 6 is a front view of the end cap for an open end of a filter housing shown in FIG. 1.

FIG. 7 is a rear view of the end cap for an open end of a filter housing shown in FIG. 1; and,

FIG. 8 is a front isometric view of the end cap for an open end of a filter housing shown in FIG. 1, shown with an environmental seal.

The dot dot dash broken line indicates cutoff boundaries for enlarged detailed portion views and forms no part of the claim.

The evenly spaced broken line showing of an environmental seal in FIG. 8 illustrates environment only that forms no part of the claim.
